ROTARY PHOTOGRAPH PRINTING
MACHINE

Galen A. Biery, Bellingham, Wash., assignor of twenty-four one-hundredths to Joseph H. Dunn and twenty-four one-hundredths to Robert F. Dunn, Bellingham, Wash.

Application March 21, 1935, Serial No. 12,154

7 Claims. (Cl. 95—77.5)

My invention relates to improvements in rotary photograph printing machines, and has for an object to provide a machine for printing photographs which may be driven at desired constant speeds and into which sheets of photographic printing paper may be fed for exposure for definite periods of time to light when in the machine contacting with photographic negatives therein and which subsequently may fall from the machine into a developing bath.

Another object of my improvement is to provide a photographic printing machine which will expose the sensitized paper for equal periods of time.

Another object of my improvement is to provide for photographic machine printing more rapidly than is possible when making the exposures by hand.

Another object of my improvement is to design a photographic printer having few and simple parts not expensive to make nor likely to get out of order.

Other objects of my invention will appear as the description proceeds.

I attain these and other objects of my invention with the mechanism illustrated in the accompanying two sheets of drawings, forming a part of this specification, in which Figure 1 is a top plan view of my rotary photographic printing machine, Fig. 2 is a sectional view of a part of Fig. 1 on the line 2—2 revolved downward through an angle of 45°, Fig. 3 is a front elevation of the lamp supporting bracket a part of which is broken away, Fig. 4 is a front side elevation of Fig. 1, Fig. 5 is a plan view of the double hinge used in the machine drawn on a larger scale shown by itself, and Fig. 6 is an edge elevation of Fig. 5.

Similar characters refer to similar parts throughout.

Certain parts are broken away to show other parts hidden thereby.

With more particular reference to designated parts: On a base 7 is fastened the bearing bracket 8 which mounts the shaft 10 for revolution. One end of the shaft 10 is centrally disposed in the closed end 9a of the hollow cylinder 9 and fastened therein. The construction provides for the revolution of the cylinder 9 on the bearing 10.

On the front end of the base is fastened the front base wall 7a, and to this wall are fastened two similar bearing brackets 28, 28 which mount the shaft 29a for revolution, disposed parallel with the elements of cylinder 9, laterally beneath the cylinder. The roller 29 is centrally mounted on the shaft 29a and fastened thereon to revolve therewith. Two bearing brackets 30, only one of

which is shown, are fastened on the base 7 and mount the shaft 31a for revolution disposed parallel with the elements of the cylinder 9 and beneath the center thereof. The roller 31 is mounted on the shaft 31a and fastened thereon to revolve therewith. Two brackets 35, 35 are fastened on the base 7 beneath the cylinder 9 and to the inclined top of each is adjustably clamped a similar bearing arm 32 by the clamping bolts 34, 34 extended through the slot 33. The shaft 37a is mounted in the bearing arms 32 for revolution parallel with the elements of the cylinder 9 and with the shafts 29a and 31a. On the shaft 37a is mounted the roller 37 fastened thereon to revolve therewith.

Over the rollers 29, 31 and 37 is placed the webbing endless belt 36 and adjusted closely beneath and against the lower part of the cylinder 9 by means of the longitudinally adjustable bearing arms 32. Fastened on the rear end of the roller shaft 29a is the pulley 67 and handle crank 68, and the cylinder 9 may be revolved in the direction indicated by the arrow in Fig. 4 by a power belt, not shown, over the pulley 67 or by hand on the crank 68.

There are four, spaced, rectangular openings, 11, 12, 13 and 14 in the peripheral walls of the cylinder 9, and in them are placed the segmental glass windows 15, 16, 17 and 18, respectively and cemented securely therein. Over each of the glass windows is placed a photographic negative, 19, and fastened in place. In practice, pieces of adhesive tape, shown at 20, serve very well to retain the negatives in place on the windows.

An electric lamp bulb housing 22 is retained in transverse and horizontal central position within the cylinder 9 by the angular bracket 21 fastened to the housing and to the base 7. The housing 22 is open at the bottom end only and thereat has the downwardly and inwardly inclined baffle plates 27, 27 to limit the beam of light which may pass therethrough from the lamp 23 mounted in the housing and connected with a service electric circuit by the wires 26.

All of the walls of the lamp housing are closely joined and opaque except the top wall 25, which is made of frosted glass, and in the front wall is set the red lens 24. The frosted glass provides a weak light beneath the glass window at the top to aid in correctly placing a negative thereover, and the red lens provides non-actinic illumination for the dark room in which the printer is used.

Four similar feed arms are pivoted at equal spaces on the edge of the open end of the cylin-

der 9. Each of the feed arms consists of the adjustable shank 38, 40 clamped together by the coupling 50, the hook 41, the nib 42 on the hook end extended at right angles therewith, and the handle 39 at an angle with the shank. The handle, shank and hook are, substantially, in the same plane while the nib is at right angles with this plane.

The double hinge 44, 47 has the hinge pins 45 and 48 at right angles with each other and, substantially, in the same plane. On one of the leaves of the hinge 44 is the longitudinal boss 43 with the hole 43^a lengthwise therethrough. The handle 39 is extended through this hole and fastened therein with its free end protruding beyond the hinge end. In each hinge, 44 and 47, the hinge eyes are preferably of an even number and the hinge pin extends at one end beyond the end of the hinge and mounts one of the coil springs 49, or 46 thereon to react between the pin head and the outer hinge eye at that end of the hinge on one leaf while the other pin head bears on the outer hinge eye on the other leaf, thus adjacent hinge eyes are forced against each other with frictional pressure by the spring reaction which provides resistance against hinge operations.

The outer leaf of hinge 47 is fastened on the interior of the cylinder wall with its hinge pin 48 parallel with the cylinder elements, the spring 49 within the cylinder, and an end of the hinge protruding outside of the cylinder wall edge. This disposition of the part 47 of the double hinge places the part 44 thereof entirely outside of the cylinder 9, as shown in Fig. 1. The disposition of the feed arms, when not in operation or being oscillated, is shown in Figs. 1 and 4 with respect to the arms shown at the top, bottom and left-hand side of the cylinder. The resistance to hinge operation caused by the springs 46 and 49, by construction, is sufficient to retain the arms in such positions as they may be at the conclusion of their operative movements.

A tipping and guide rod is bent to provide a handle 52, a standard 53 at right angles with the handle, an inclined lateral 53^a at an angle with the standard, and the tipping arm 54 parallel with the handle 52. The handle 52 is extended into a hole in the bracket 51 and fastened therein. The bracket 51 is fastened to the base wall 7^a to dispose the handle 52 horizontally and the standard 53 extending upwardly and outwardly and the arm 54 horizontal with its free end outside of and adjacent the plane of the open end of the cylinder 9. The parts 53 and 53^a serve as guides and incline away from the end of the cylinder, as shown in Fig. 1.

Two parallel sensitized-paper guides 55, 55 are mounted on the base wall 7^a and fastened thereon by the angle brackets 56, 56 and disposed with their plane at an inclination of about 45° with the horizon inclined downward toward the cylinder 9 with their lower ends adjacent the cylinder and the roller 29 and the belt 36 thereover. The upper and outer ends of guides 55 are spaced by the crossbar 57 fastened to the bottoms thereof. On the top wall of the front guide 55 near its lower end is fastened the upward-incline elevator guide 66. Between the guide 66 and the lower end of the said guide 55 on top of the said guide 55 is fastened the angle-bar guide 65 with its ends projected beyond the said guide 55 and its outer end nearer the lower end of the guide 55 than is its upper end; that is, it is in a plane parallel with and above the plane of the guides 55,

55 and inclined with respect to these guides. A slot opening 58 is made in the rear wall of the rear guide 55 and the lugs 59 and 60 extend rearwardly from the said rear wall, one at each end of the slot. The shoe 61 is extended through the slot 58 into the guide slot of the rear guide 55 and its rearwardly projected arm 63 is pivoted to the lug 59 for oscillation in the guide slot. The stop 61^a on the free end of the shoe 61 bears on the outer wall of the guide 55 when the shoe is at its maximum position within the guide slot. The spring 64 is stretched between the shoe arm 63 and the lug 60 to react and tend to retain the shoe within the guide slot. A light pressure outward against the inner edge of the shoe 61 will move the shoe to its outward position, shown in dotted lines at 61', against the reaction of the spring 64.

In operation: It is assumed that the roller 29 is being revolved in a counter-clockwise direction, driving the cradle belt 36 and revolving the cylinder 9 in a clockwise direction. A piece of sensitized photographic paper of dimensions suitable for printing from the negatives 19 is inserted flatwise in the guides 55 with its upper edge at the dotted line at A in Fig. 1. The revolving cylinder will cause the outer end of the handle 39, on one of the feed arms, to bear on the tipping arm 54 and oscillate the said feed arm on a hinge pin 48 till it is disposed in the position shown in dotted outlines in Fig. 4 when the handle 39 thereof may pass the tipping arm. At this time the feed arm handle is at 39', the outer hinge pin at 45', the inner hinge pin at 48', the attached hinge leaf at 47', the shank at 38' 35 and the hook nib at 42'. Continued revolution of the cylinder 9 will cause the hook 41 to bear on the front guide 55 near the upper end thereof and as the said hook moves downward on the guide, under the pull of the revolving cylinder, the nib 42 will bear on the upper edge A of the said photographic paper and push the same downward in the guides 55 till the top edge of the paper reaches its dotted position at A' when the lower edge of the said paper will have been caught between the cylinder 9 and the belt 36 at the junction thereof and thereafter will be drawn further in between the cylinder and belt and the feeding pressure from the nib 42 is no longer required. However, the movement of the said nib and the periphery of the cylinder are so nearly the same that continued contact of the nib on the paper edge as both are drawn downward will not injure the paper.

The said feed arm hook continues moving downward while bearing on top of the said guide 55, being drawn by the revolving cylinder 9, till it reaches the upper end of the inclined elevator guide 66 when it is raised above the guide 55 as it passes along the top of the inclined guide, till on reaching the lower end of the guide 66, which is relatively the highest part of the said guide, the hook nib 42 is above the bottom flange of the angle-bar guide 65 and the hook 41 drops from the guide 66 and falls till the nib 42 bears on the said bottom flange of the angle bar 65. As the hook proceeds downward it bears against the standing flange of the guide 65 and is drawn laterally by this inclined flange till when it passes the outer end thereof the nib end of the hook 41 is in front of the front end of cylinder 9 with a space therebetween, as shown in Fig. 1.

By construction, the piece of sensitized paper fed into the printer between the cylinder and belt by the feed arm, as described, will make desired

register with the negative 19 which is shown in Fig. 1 as being on the glass 16; and, as the belt and cylinder continue to move with the sensitized paper therebetween, in due course it will pass beneath the lamp 23 light from which will pass through the glass and the uncolored areas of the negative and produce the results expected in such cases and print the paper which continues between the negative and belt till it is dropped over the turn in the belt, when passing over the roller 37, into the developing bath.

Meanwhile, the next feed arm in order has gone through with the same movements as described above and pushed another piece of sensitized paper between the belt 36 and the negative on the glass 16, which has passed beneath the lamp 23 and has been printed as above described.

If the belt 36 be power driven, the operator need only place pieces of the sensitized paper into the upper ends of the guides 55 and move them downward, one at a time, till the upper edge thereof is within reach of the next descending hook nib.

During the oscillation of the feed arm which occurs while the feed arm handle and the tipping arm are engaged, the shank 33, 40 of the feed arm contacts with the guides 53 and 53^a and the feed arm is turned thereby on the hinge pin 45 from its position where the nib 42 is in front of the cylinder 9 to its position where the said nib 30 is between the guide bars 55, as shown in Fig. 1.

During the passage of the pieces of sensitized paper in the guides 55 they are moved transversely by the shoe 61 to bear against the front one of the guides 55. The paper thus is aligned with this guide in cases where there is a slight difference in the width thereof.

Having thus disclosed my invention, what I claim as new therein and desire to secure by Letters Patent is,—

40 1. A photograph printing machine including, a set of belt rollers mounted for revolution, an endless belt over the said set of rollers to be driven thereby, means to drive one of the said rollers, a hollow cylinder, having openings through the walls thereof, open at one end and the other end thereof fastened to a centrally disposed shaft thereon, means to mount the said cylinder shaft for revolution disposing the said cylinder on the said belt to be revolved thereby, segmental glass windows fastened in the said cylinder wall openings, means to fasten photograph negatives on the said glass windows, means to feed in, one at a time, sensitized photographic papers between the said negatives and the said belt, and means 50 to direct light through the said photograph negatives on to the said sensitized photographic papers on the said belt while the cylinder, negative, sensitized paper and belt move simultaneously at the same rate.

60 2. A rotary photograph printing machine including, a drivable endless belt, transparent cylindrical walls mounted for revolution by and on the said belt, photograph negatives fastened on the said transparent cylindrical walls, means to feed sensitized photographic paper between the said photograph negatives and the said belt, an electric lamp disposed to direct light through the said transparent walls, negatives thereon and on to the said sensitized photographic paper as the 65 said walls, negatives, paper and belt move simultaneously at the same rate past the said lamp, and means to drive the said belt.

70 3. A rotary photograph printing machine including, an endless belt mounted for being driven, means to drive the said belt, transparent cy-

lindrical walls mounted for revolution on and by the said belt, photograph negatives fastened on the said transparent cylindrical walls, a pair of guides disposed endwise adjacent the junction between the said cylindrical walls and the belt adapted to direct sensitized photographic papers between the said walls and belt, means to feed the said sensitized paper through the guides to be engaged between the moving transparent cylindrical walls and belt to register with the 10 said photograph negatives, and an electric lamp disposed to direct light through the said transparent walls, photograph negatives and on to the said sensitized paper as they together move past the said lamp.

15 4. A rotary photograph printing machine including, an endless belt mounted for being driven, means to drive the said belt, a hollow cylinder having transparent areas mounted for revolution on and by the said belt, a photograph negative fastened over each of the said transparent areas, a pair of guides disposed endwise adjacent the junction between the said cylinder and belt adapted to direct sensitized photographic papers between the said cylinder and belt, feed 20 arms each having a hook and being connected to the said cylinder by a double hinge disposing the hook to bear on the outer edge of one of the said sensitized papers in the said guides to push the paper between the cylinder and belt in register with one of the said photograph negatives as the cylinder and belt together move, and an electric lamp disposed to direct light through the said transparent areas, the photograph negatives thereover and on to the said sensitized papers 25 between the said negatives and belt as they together move past the said lamp.

30 5. A rotary photograph printing machine including, an endless belt mounted for being driven, means to drive the said belt, a hollow cylinder having a plurality of transparent areas mounted for revolution on and by the said belt, a photograph negative fastened over each of the said transparent areas, a pair of guides disposed endwise adjacent a junction of the said cylinder 40 and belt adapted to direct sensitized photographic papers between the cylinder and belt at the said junction thereof, a plurality of feed arms each having a handle, a shank and a hook disposed adjacent the cylinder and connected therewith by a frictional double hinge, a stationary arm adjacent the said cylinder disposed to engage the outer end of each of the said feed-arm handles as they move with the cylinder and oscillate the feed arm on one hinge pin of the said double hinge to dispose the feed-arm hook farther from the said cylinder, a stationary inclined guide disposed to bear on the shank of the said feed arm while being oscillated and swing the feed arm on the other hinge pin of the said double hinge to 45 dispose the feed-arm hook above the said sensitized-paper guides to engage the top edge of one of the sensitized photographic papers and push the said paper between the said cylinder and belt disposed to register with one of the said photograph negatives as the said cylinder revolves, an inclined elevator guide to raise the said feed-arm hook out of engagement with the said paper, an inclined angle bar guide to swing the said feed-arm hook on the said other hinge pin from over the said paper guide to its said position in front of the said cylinder, and an electric lamp disposed to direct light through the said transparent areas, the photograph negatives thereover and on to the said sensitized papers 50

55 60 65 70 75

registering with the said sensitized papers.

said negatives and between the said negatives and belt as they move together past the said lamp.

6. In combination, an endless belt mounted for being driven, means for driving the said belt, a hollow cylinder having a transparent area in the walls thereof mounted for revolution on the said belt, a photograph negative fastened over the said transparent area, a pair of guides disposed endwise adjacent a junction of the said cylinder and belt adapted to direct a sensitized photographic paper to the said junction, means to push the said paper in the said guides between the said cylinder and belt at the said junction thereof disposed to register with the said photograph negative, and means to direct light through the said transparent area, the said photograph negative and on to the said sensitized paper as they revolve together on the said belt.
7. In combination, an endless belt mounted for being driven, means for driving the said belt, a

hollow cylinder having a transparent area in the walls thereof mounted for revolution on the said belt, a photograph negative fastened over the said transparent area, a pair of guides disposed endwise adjacent a junction of the said cylinder and belt adapted to direct sensitized photographic paper to the said junction, a pivoted, spring-pressed shoe mounted for transverse oscillation in one of the said pair of guides to bear on a side edge of any paper passing through the guides and press the paper against the edge of the other one of the said guides, means to push sensitized photographic paper through the said guides into the said junction of the cylinder and belt disposing the same in register with the said photograph negative, and means to direct light through the said transparent area, the said photograph negative and on to the said sensitized photographic paper as they together revolve on the said belt.
